UNITED STATES PATENT OFFICE.

WILLIAM H. SAUVAGE, OF NEW YORK, N. Y.

HAND-BRAKE.

1,263,123.

Specification of Letters Patent. Patented Apr. 16, 1918.

Application filed March 16, 1915. Serial No. 14,660.

To all whom it may concern:

Be it known that I, WILLIAM H. SAUVAGE, a citizen of the United States, residing at New York, in the county of New York and State of New York, have invented certain new and useful Improvements in Hand-Brakes, of which the following is a specification.

This invention relates to brake mechanism 10 for vehicles, and in its more intense aspect, to mechanism associated with hand brakes.

One of the objects of the present invention is to provide a simple and practical hand brake having high speed, high power and 15 quick acting features. Another object is to provide a hand brake of the above general character having relatively few parts which will be inexpensive to manufacture and assemble. A further object is to provide a 20 hand brake mechanism which will be reliable and efficient under all conditions. A further object is to provide a mechanism of the first above mentioned character which will be automatic in operation and will require no further effort, mental or physical, 25 than that required to operate hand brakes now in general use.

Other objects will be in part obvious from the annexed drawings and in part indicated 30 in connection therewith by the following analysis of this invention.

This invention accordingly consists in the features of construction, combination of parts and in the unique relations thereof, all 35 as more completely outlined herein.

To enable others skilled in the art so fully to comprehend the underlying features thereof that they may embody the same by the numerous modifications in structure and 40 relation contemplated by this invention, drawings depicting several desired forms have been annexed as a part of this disclosure, and in such drawings, like characters of reference denote corresponding parts 45 throughout all the views, of which:

Figure 1 is a sectional elevational view of such parts of a brake mechanism as will be necessary to understand the present invention:

Fig. 1^a is a detail view showing the parts 26 and 27 illustrated in Fig. 1;

Fig. 2 is a sectional plan view of the upper portion of said mechanism;

Fig. 3 is a view similar to Fig. 1 showing a modified form of brake mechanism;

Figs. 4 and 4^a are detailed views of a square hollow pawl;

Fig. 5 is another view similar to Fig. 1 showing a third modification;

Fig. 6 is a detailed sectional view of the parts shown in Fig. 5 in operative position.

In order that others may have a clearer perception of the various objects within the contemplation of the present invention it may be noted by way of explanation that all 65 electric street cars, suburban, freight or passenger cars and the like are compelled under the regulations of all States to have a hand brake, although provided with air brakes, as it is well recognized that they are more reliable in use than air brakes which occasionally fail to act at a most desired or critical moment. Were it not for the hand brake, which in most cars is now considered in the nature of an emergency brake, the car might 70 travel for some considerable distance before being brought under control. This would be especially noticeable in heavy high speed suburban cars. In these cars the hand brake mechanism now in general use is open to the 75 serious objection that in order to obtain the desired power to initially apply the brakes a relatively small winding drum is used in proportion to the radius of the operating handle and usually four or five turns of this 80 handle are required before the normal or necessary slack in the brake chains or rigging is taken up prior to the actual operation 85 of the brake shoes upon the peripheries of the wheel. Two or three seconds are required at least in making these turns and in that length of time a car traveling thirty miles an hour will move at least seventy five or a hundred feet before the brakes begin to act and at least again that distance before 90 the car is brought under control.

The present device is designed and intended to take up the necessary slack required in the operative brake rigging almost instantaneously and result in the immediate 100 application of brakes without materially increasing the amount of strength required to operate the brakes or adding to the mental effort of the operation by requiring other mechanical movements than those to which 105 the operator is accustomed.

As will now be pointed out in detail by reference to the accompanying drawings and more particularly to Fig. 1, the simplicity and practicability of the present construction will be apparent. There is denoted at 10 the brake staff which may be assumed to be mounted upon the front platform 11 of an electric street car and is provided at its upper end with the usual operating crank handle, not shown. This staff extends downwardly through the platform a slight distance and has its lower end 12 mounted in a bearing bracket 13 suspended from the under side of the car. Above the bracket and rigidly secured to the staff by means of a bolt 14 is a sleeve or winding part 15 to which is attached the end link 16, as shown in section of a chain extending rearwardly as indicated by the dotted lines about a sheave pulley 17, thence back to a sheave or second winding part 18 also mounted upon the same staff 10. The end of the chain is secured thereto by means of a bolt 20 having a counter sunk head 21 on the inner side of the sheave.

It will thus be seen that as the staff 10 is turned both ends of the chain will be wound thereabout directly and in the same direction, one on the large sheave or drum 18 and the other on the smaller sheave 15 thereby quickly to take up the excess slack in that part of the brake rigging. It is, of course, to be understood that the pulley 17 is connected in any desired manner with the brake rigging proper.

The upper brake chain preferably has a large ring or link 19 attached close to the pulley or sheave wheel, whereby should mechanism get out of order the lower chain, 40 and staff 10 would constitute a direct acting brake to rely upon, as the link would stop in the pulley fork as shown diagrammatically.

The large drum 18 is threaded onto a sleeve 22 loosely mounted upon the staff 10 and provided with cut away portions 23 adapted to contain lubricant, for example, and thereby reduce the friction when these parts turn relatively to each other under circumstances as will hereinafter appear more clear. The sleeve 22 and the drum carried thereby are normally held in raised position by means of a coiled spring 24 resting in a grooved collar 25 supported upon the sleeve 15. The drum is provided with a lower recess 26 adapted to co-act with a projection 27 on this collar 25 as shown in Fig. 1^a to insure uniform rotation of the drum and collar 18 and 25 at all times and the upper part of the drum is provided with another stop 29 coacting with a downwardly projecting portion 31 upon a fixed bearing member 32 which is rigidly secured to the floor of the car as by means of screws 33.

This bearing member 32 is provided with

an annular flange 34 within which is a 65 ratchet or toothed ring 35 adapted to co-act with a correspondingly serrated surface 36 on the under side of a disk 37 constituting the upper part of the bearing member 22.

The upper surface of this disk 37 is provided with a plate 40 having a shallow semi-spherical pocket within which normally rests a case hardened roller bearing such as a ball or roller 41. The upper half of the ball being normally embedded in a second semi-spherical hardened pocket, of greater depth than the first mentioned pocket, in a rectangular plate 42 which is held against relative movement with respect to the staff 10 by being keyed thereto and positioned in a rectangular chamber 43 mounted upon the squared portion 44 of the staff 10. This casting 43 is provided with a circular ratchet 44' about its lower outer part adapted to be engaged by a pivotally mounted manually operated dog 45 upon the bearing member or casting 32.

From this description, it will be clear that as the brake handle is rotated, motion will be transmitted directly to the sleeve or smaller winding part 15 which is positively secured thereto to wind up that end of the chain connected therewith. Motion will also be transmitted through the casing 43, ball 41 and bearing member 22 to rotate the large drum 18 a corresponding amount, thereby to easily and quickly wind up the necessary slack in the chain connecting the brake mechanism with the brake rigging beneath the car. A quarter turn of each drum is usually sufficient to remove this slack.

As soon, however, as the slack is taken up and a material strain above a predetermined load is exerted or reacted upon the large drum due to the effective application of the brake shoes to the peripheries of the wheels, the ball or roller 41 will ride up out of the shallow pocket in the plate 40 relatively speaking, and force this plate and bearing 22, together with the drum 18 carried thereby downwardly, until the ratchet surfaces 35 and 36 engage and positively lock the parts against any rotative movement. The brake staff, however, continues its rotation, the ball 41 riding about on the upper surface of the plate 40, and effectively transmits power through the sleeve 15 to apply the brakes. The dog 45 is manually operated to take into the teeth of the ratchet 44' to hold the brakes when desired.

On release of the brakes the tail of the dog 45 is pushed in in the usual manner to release the ratchet which permits the ball 41 to roll back into the pocket of the plate 40 which releases the ratchet surfaces 35 and 36 and allows the drum to return to normal position. It is thus seen that a high speed, high power and quick acting brake mecha-

nism is provided having relatively few parts, which mechanism is cheap to manufacture and not likely to get out of order.

In the mechanism shown in Fig. 3 substantially the same principle of operation occurs. Referring to this figure in detail the staff 10 passes down through the car floor 11 and has its lower end 12 mounted in a bracket 13 as previously described. Intermediate the 10 floor and the bracket is provided a connection 50 for securing one end of the chain adapted to be wound about the staff which in this case is one of the winding parts as the brakes are applied. This chain passes 15 over a loose pulley as shown in Fig. 1 and has its opposite end connected at the point 51 to the relatively large winding drum 52. Positioned on a squared portion of the staff and below a holding collar 53 is an annular 20 disk 54 carrying a plurality of roller bearings 55 the lower parts of which rest in semi-cylindrical pockets in the upper part of the drum 52.

The lower part of this drum is provided 25 with a radially serrated surface or ratchet 56 and a stop arm 57 adapted to co-act with a stop 58 projecting upwardly from the bracket support 13. A spring 60 normally urges this winding drum to its upper position, as shown. When, however, the slack 30 has been taken up and the strain exerted upon said drum exceeds the torsional strength of the clutch connection between the disk 54 and drum, the rollers 55 will ride out of the semi-cylindrical pockets and engage the upper surface of the drum thereby to force the drum 52 downwardly and cause the ratchet surface 56 to engage an automatic spring pressed pawl 61. This pawl is mounted 35 in a pocket 62 and held in raised position by means of the spring 63 with its flange 64 engaging the upper part of the pocket 62, as shown. This ratchet and pawl co-operate one with another in a manner to prevent positively a reverse winding of the drum to release the braking power until desired.

On the upper surface of the platform or floor 11 is keyed to the staff 10 the usual ratchet wheel 65 adapted to be engaged by 50 the manually operated pawl 66 at one side thereof in the usual manner.

This construction as the other is entirely automatic in its operation and is manipulated in exactly the same manner so far as 55 the operator is concerned as brakes now in general use and does not in any way require an additional mental effort on the part of the operator to apply the brakes through this mechanism to that to which he has heretofore 60 been accustomed. The importance of this feature is readily appreciated when an emergency application is required.

This operation is substantially as follows: On applying the brakes the staff 10 is ro-

tated by the brake handle in the usual manner which causes a rotation of the connection 50 to wind one end of the chain about the staff and also transmits power through the disk 54 and rollers to the drum 52 to wind up the excess slack on the opposite end of the 65 chain. As soon, however, as this slack has been taken up by approximately a quarter turn and a real effective braking power is exerted upon the periphery of the wheels, the torsional strength of this connection is 70 overcome and causes the rollers 55 to ride up out of the pockets and force the drum down into locked position which positively prevents a loss of braking power through 75 this end of the chain under all conditions 80 until such is desired by the manual release of the brake handle. The pawl 66 may be called into play to hold the ratchet wheel 66 against reverse rotation and hold the brakes applied at any desired degree. In emergency 85 applications, it is sometimes desirable to give the brake handle a quarter turn by a pull stroke rather than a push stroke. The pawl is actuated to hold the ratchet 65 while the handle is moved back a quarter stroke 90 by means of the handle ratchet mechanism of well known construction in order that the operator may make a second short pull stroke.

It is to be noted that the operation of the 95 pawl 66 is entirely separate and independent from the automatically operated pawl 61, thereby positively preventing any release of the brakes during this emergency application.

When it is desired to release the brakes the pawl 66 is kicked off in the usual manner which allows the ratchet 65 to rotate with the staff 10 and carry the disk 54 back to such position as to permit the drum 52 to 105 rise under the action of the spring 60, thereby releasing the ratchet 56 from the automatic independently operating pawl 61 and allowing the drum to turn until the stop arm 57 co-acts with the fixed stop 58 in the normal 110 position of the parts.

There is shown in Fig. 5 a third modification involving substantially the same principle of braking mechanism. In this modification, the larger part of the mechanism is 115 mounted above the car floor 11 and about the staff 10, the lower part of this staff rests in the bracket 13 as before described and is provided with a connection 70 for the high power end of the chain and a relatively large 120 winding drum 71 for the low power end of the chain. This drum 71 is threadedly connected with a sleeve 72 to which is secured a ratchet 73, having relatively shallow semi-spherical pockets in its upper surface in 125 which rests roller or ball bearings 74 co-operating with a second ratchet disk 75 mounted thereabove. The ratchet 73 is

adapted to be engaged by an automatic independently operating spring pressed pawl 76 at one side, while the ratchet 75 is engaged by the manually operated or foot pressed pawl 77 at the opposite side. A spring 78 normally urges these disks into close relation by reacting against a cap 80 keyed to the staff and provided with ratchet stops 81 engaging with stops 82 upon the upper surface of the ratchet disk 75. The lower part of the disk 75 is provided with a smooth hardened surface 83 adapted to co-act with an inclined cam 84 upon the upper surface of the nose of the spring actuated pawl 76, thereby to engage and automatically disengage the dog 76 with the ratchet 73 on release of the brake staff when the rollers drop back into the pockets upon the upper surface of the disk 73.

20 The operation of this device is substantially as follows:

On rotating the staff 10 by the brake handle in the usual manner, both ends of the chain will be wound about the staff and 25 drum 71 respectively until the normal slack has been taken up after which the pull upon the upper end of the chain exceeds the predetermined load and becomes sufficiently great to cause a separation of the plate 73 and 75 by reason of the roller 74 rotating 30 out of the pockets in the lower disk. On such movement the spring actuated pawl 76 immediately comes into engagement with the ratchet 73 in such a manner as to positively prevent an unwinding of the drum 35 during the subsequent operations of the mechanism or until it is intentionally desired to release all pressure. The brakes may be held at a predetermined degree of tension by 40 the operator or he may actuate the pawl 77 to engage the ratchet 75 to hold the same for a considerable length of time without effort on his part.

From the description of these several 45 modifications, it is to be seen that all complicated gearing is eliminated. Both ends of the chain are wound positively and directly about the staff in the same direction until such time as the slack is positively 50 taken up whereupon the large winding drum automatically disconnects and locks itself in a stationary position until released by hand. The independently operating dogs eliminate any possible chance of an accidental release of the brakes during their 55 application thus making the device more practical, reliable and efficient under all conditions. It is, therefore, believed that the present invention provides a simple and 60 practical device adapted to accomplish, among others, all of the advantages and objects above set forth.

Without further analysis, the foregoing will so fully reveal the gist of this inven-

tion that others can by applying current 65 knowledge readily adapt it for various applications without omitting features that, from the standpoint of the prior art, fairly constitute essential characteristics of the generic or specific aspects of this invention, 70 and therefore such adaptations should and are intended to be comprehended within the meaning and range of equivalency of the following claims.

75 I claim

1. In a brake mechanism, in combination, a device comprising a pair of winding parts of different size for applying the brake shoes to the wheels, means for automatically varying the braking power according 80 to the degree of pressure exerted in applying the brakes by causing relative movement of one part in the direction of the axis of the other and means for locking both winding parts against reverse rotation one 85 of which locking means is automatic in its operation and independent of the other.

2. In a brake mechanism, in combination, two winding means of different size for applying the brake shoes to and exerting a 90 pressure on the wheels, means for automatically cutting one winding means out of action, an automatic positively acting member adapted to hold the larger winding means against rotation above a predetermined 95 load until the brakes are released intentionally and means for automatically releasing said automatic holding part when the brakes are intentionally released.

3. In a brake mechanism, in combination, 100 a winding drum for taking up slack and applying the brake shoes to the wheels, a winding means including a drum for applying the brake shoes with the maximum power, automatic means for cutting the 105 winding drum out of action when a predetermined strain is exerted, means for preventing backward rotation of said maximum power winding means and means independent of said last mentioned means for 110 positively preventing an unwinding of the drum as further movement of the maximum power winding means takes place.

4. In a brake mechanism, in combination, 115 two winding parts primarily operating to take up slack and apply the brake shoes to the wheels, a clutch device normally connecting said parts, a stationary member and means dependent on a predetermined load 120 on the brakes for operating said clutch device to throw one of said parts out of action by a relative longitudinal movement of said part and into clutched engagement with said stationary member.

5. In a brake mechanism, in combination, 125 a winding drum for taking up the slack and applying the brake shoes to the wheels, winding means adapted to apply

- the brake shoes to the wheels with the maximum braking power, means operating at a predetermined degree of braking pressure for cutting the drum out of action including roller means adapted to cause a longitudinal relative movement of said drum, and means for automatically holding the drum in locked position.
6. In a brake mechanism, in combination, a winding drum for taking up the slack and applying the brake shoes to the wheels, automatic locking means for said drum operative after the slack has been taken up, a winding means adapted to apply the brake shoes to the wheels with the maximum braking power, means governed by the degree of force exerted in braking for throwing the drum out of operation and causing a movement of the drum in the direction of its axis into an independent positively locked position.
7. In a brake mechanism, in combination, two winding parts primarily operating to take up the slack and apply the brake shoes to the wheels, means adapted to automatically throw one of said parts out of action upon the braking pressure attaining a predetermined degree, and automatically operating means for holding said thrown out part against rotation until the braking pressure is reduced to below said predetermined degree.
8. In a brake mechanism, in combination, a device comprising a pair of winding parts of different size for applying the brake shoes to the wheels, means adapted to cause relative movement of one part in the direction of the axis of the other to disconnect the same from low to high power gear for automatically varying the braking power according to the degree of pressure exerted in applying the brakes, and means for automatically and positively locking the moved part against reverse rotation on such movement.
9. In a brake mechanism, in combination, two winding parts primarily operating to take up the slack and apply the brake shoes to the wheels, a clutch device normally connecting said parts, means dependent on a predetermined action of the brakes for operating said clutch device to throw one of said parts out of action by a relative longitudinal movement, and an automatic independently operating member adapted to hold said part against rotation on such movement.
10. In a brake mechanism, in combination, a device comprising a pair of winding parts of different size for applying the brake shoes to the wheels, a brake staff upon which both of said parts are mounted whereby they rotate in the same direction, means for automatically varying the braking power created in proportion to the degree of pressure exerted in applying the brakes, and two separate and independent means for locking said pair of winding parts against reverse rotation, one of said means being automatic in its operation and the other foot controlled.
11. In a brake mechanism, in combination, a device comprising a pair of winding parts of different size for applying the brake shoes to the wheels, a brake staff upon which both of said parts are mounted, and means for automatically varying the braking power created in proportion to the degree of pressure exerted in applying the brakes, said means comprising a pair of plates on said staff in spaced relation to each other normally relatively connected, one of which is fast on said brake staff and the other operatively positioned with respect to one of said winding parts, and means for moving said plates relatively apart in the direction of their axes to disconnect them and lock one of said winding parts.
12. In a brake mechanism, in combination, a device comprising a pair of winding parts of different size for applying the brake shoes to the wheels, a brake staff upon which both of said parts are mounted, a stationary member, and means for automatically varying the braking power created in proportion to the degree of pressure exerted in applying the brakes, said means comprising a pair of normally connected plates on said staff in spaced relation to each other, one of which is fast on said brake staff, and means associated with said plates adapted to cause their disconnection and stop the winding action of one of said first mentioned winding parts by moving the same into locking engagement with said stationary member.
13. In a brake mechanism, in combination, a device comprising a pair of winding parts of different size for applying the brake shoes to the wheels, a brake staff upon which both of said parts are mounted, and means for automatically varying the braking power created in proportion to the degree of pressure exerted in applying the brakes, said means comprising a pair of recessed plates on said staff in spaced relation to each other and normally relatively connected, one of said plates being fast on said brake staff, and roller means normally occupying said recesses in said plates adapted to roll out of one of said recesses and cause a movement of one of the plates in the direction of the axis of the staff thereby disconnecting said plates, and means adapted to lock one of said plates and one of said winding parts against further rotation when such axial movement takes place.
14. In a brake mechanism, in combination, a device comprising a pair of winding parts of different size for applying the brake

- shoes to the wheels, a brake staff upon which said parts are mounted, and means for automatically varying the braking power created in proportion to the degree of pressure exerted in applying the brakes, said means comprising a pair of recessed plates on said staff in spaced relation to each other and normally rotatively connected, one of said plates being fast on said brake staff, roller means normally occupying said recesses in said plates adapted to roll out of one of the recesses and cause a movement of one plate in the direction of the axis of the staff thereby disconnecting said plates, means adapted to lock one of said plates and one of said winding parts against further rotation when such axial movement takes place, and a manually operated pawl and ratchet mechanism associated with the other of said plates adapted to hold the same at will temporarily in the position to which it is moved.
15. In a brake mechanism, in combination, a device comprising a pair of winding parts of different size for applying the brake shoes to the wheels, a bearing secured to the floor of the car, a sleeve mounted in said bearing to which the larger of said winding parts is connected, a ratchet associated with said sleeve, a co-acting ratchet associated with said bearing, and means adapted to force said ratchets into operative relation and prevent relative movement of said larger winding part.
16. In a brake mechanism, in combination, a device comprising a pair of winding parts of different size for applying the brake shoes to the wheels, a bearing secured to the floor of the car, a sleeve mounted in said bearing to which the larger of said winding parts is connected, a ratchet associated with said sleeve, a coacting ratchet associated with said bearing, and means adapted to force said ratchets into operative relation and prevent relative movement of said larger winding part, said means comprising a recessed member, a roller bearing partially embedded in said recess adapted to ride out of said recess on rotation of the brake staff.
17. In a brake mechanism, in combination, a device comprising a pair of winding parts of different size for applying the brake shoes to the wheels, a bearing secured to the floor of the car, a sleeve mounted in said bearing to which the larger of said winding parts is connected, a ratchet associated with said sleeve, a coacting ratchet associated with said bearing, and means adapted to force said ratchets into operative relation and prevent relative movement of said larger winding part, said means comprising a pair of
- recessed members, a roller bearing partially embedded in said recesses adapted to ride out of one of said recesses on rotation of the brake staff and bodily separate said members, and spring means for returning said parts to normal position upon the release of the brakes and preventing an unwinding of said larger winding part.
18. In a brake mechanism, in combination, a device comprising a pair of winding parts of different size for applying the brake shoes to the wheels, a bearing in the car floor having a pawl mounted on one side thereof, a ratchet on the upper part of the bearing, a sleeve having a coacting ratchet mounted in said bearing adapted to carry the larger of said winding parts, and means for forcing said two ratchets into coactive relation comprising a plate having a recess, a roller resting in said recess, a carrier for said roller adapted to move on rotation of the brake staff to carry the roller out of said recess, thereby to cause a longitudinal movement of the sleeve to effect a locking of the ratchet surfaces and prevent further rotation of the larger winding part, and a ratchet associated with said roller carrier adapted to be engaged by said pawl at will temporarily to hold the parts in braking position.
19. In a brake mechanism, in combination, a device comprising a pair of winding parts of different size for applying the brake shoes to the wheels, a bearing in the car floor having a pawl mounted on one side thereof, a ratchet on the upper part of the bearing, a sleeve having a coacting ratchet mounted in said bearing adapted to carry the larger of said winding parts, and means for forcing said two ratchets into coactive relation comprising a plate having a recess, a roller resting in said recess, a carrier for said roller adapted to move on rotation of the brake staff to carry the roller out of said recess thereby to cause a longitudinal movement of the sleeve to effect a locking of the ratchet surfaces and prevent further rotation of the larger winding part, a ratchet associated with said roller carrier adapted to be engaged by said pawl at will temporarily to hold the parts in braking position, and a spring adapted to coact with said larger winding part to cause a separation of the two ratchet surfaces after the smaller winding part is unwound.
